COAXIAL TRANSMISSION LINE FILTER

Paul I. Richards, Cambridge, Mass., assignor to
the United States of America as represented
by the Secretary of War

Application January 3, 1946, Serial No. 638,899

1 Claim. (Cl. 178—44)

1

This invention relates generally to electrical apparatus and more particularly to an "m"-derived type, coaxial band-pass filter.

In the "m"-derived type filter the attenuation of a signal within a pass band of frequencies between the cutoff frequencies is low while the attenuation on either side of the pass band rises sharply. The "m"-derived type filter is also unique in that for two arbitrarily chosen frequencies in the suppression region, the attenuation may be made theoretically infinite.

The use of lumped-constant filters becomes more and more impractical as the frequency of operation is increased. It is an object of this invention to provide an "m"-derived coaxial band-pass filter which may be used at relatively high radio frequencies. Still another object is to provide a band-pass filter wherein the attenuation rises sharply on either side of the pass band until it reaches an infinite value at two chosen frequencies. It is a further object to provide a coaxial band-pass filter which may be readily inserted or removed from a standard radio frequency transmission line.

Other objects, features and advantages of this invention will suggest themselves to those skilled in the art and will become apparent from the following description of the invention taken in connection with the accompanying drawings in which:

Fig. 1 is a cross-sectional view of a coaxial band-pass filter embodying the principles of this invention;

Fig. 2 is a schematic diagram of a lumped-constant "m"-derived band-pass filter; and

Fig. 3 is a typical graph of the filter characteristics in which the attenuation of a signal input effected by the filter is plotted against a representative frequency range.

Referring specifically to Fig. 1, the filter consists of an outer coaxial conductor 13, an inner conductor 10 comprising two folded sections of transmission line effectively in series with each other, and two coaxial shunt stubs 20 and 21.

In the filter the outer diameter of a section of the inner conductor 10 is reduced to a size shown approximately by center conductor 11. The outer wall of the inner conductor 10 is extended to form a cylindrical conductor which is coaxial about said center conductor 11. Approximately at the midpoint of the center conductor section 11, the cylindrical conductor mentioned above is divided to form two separate sections 12 and 14, hereinafter referred to

2

as folded transmission line sections or, more briefly, folded sections. The space between the cylindrical conductors will be referred to as the center gap 15.

5 The first folded section of length L_1 is formed by cylindrical conductor 12 coaxially centered about center conductor 11. The second folded section of length L_2 is formed by the cylindrical conductor 14, also coaxial about center conductor 11 although separated from the first folded section by center gap 15.

10 Two coaxial shunt stub sections are formed by joining two coaxial lines 20 and 21 at right angles to the coaxial filter. Center conductor 22 of stub section 20 makes contact with cylindrical conductor 12 and is located at a predetermined distance from the center gap to be described later. Center conductor 23 of stub section 21 makes contact with cylindrical conductor 14 and is located at a predetermined distance from the center gap to be described later.

15 The filter is terminated at the end thereof with standard transmission line connectors 24 and 25 which enable the filter to be readily inserted or removed from a radio frequency transmission line.

20 The filter described above is analogous to the "pi" section "m"-derived, lumped-constant filter structure shown in Fig. 2. The lumped-constant "m"-derived type filter is well known to those skilled in the art and may include two parallel tuned circuits 52 and 53 connected in series between one input terminal 50 and one output terminal 54. Input terminal 50 and output terminal 54 are connected by parallel resonant circuits 56 and 57, respectively, to a common input-output terminal 51.

25 The relative attenuation imposed by a typical "m"-derived, band-pass filter for a band of signal inputs of different frequencies is shown by the graph in Fig. 3. The upper and lower cutoff frequencies are designated by f_1 and f_2 respectively in Fig. 3. The pass band includes all those frequencies between the upper and lower cutoff frequencies where the attenuation of a signal input is relatively low or zero. The suppression region is included in a band of frequencies below the lower cutoff frequency and a band above the upper cutoff frequency where the attenuation of a signal input is relatively high.

30 In the "m"-derived type filter the attenuation of a signal input of frequency f_3 in the suppression band below the lower cutoff frequency,

and of a signal input of frequency f_4 in the suppression band above the upper cutoff frequency theoretically is infinite. The frequencies f_3 and f_4 will hereinafter be referred to as the infinite attenuation frequencies.

In the design of the "m"-derived type, coaxial band-pass filter shown in Fig. 1, the first folded transmission line section L_1 , which is formed by the concentric cylinder **12** and center conductor **11**, is one-fourth of the wave length of the lower infinite attenuation frequency, f_3 , in length. The second folded transmission line section L_2 , which is formed by concentric cylinder **14** and center conductor **11**, is one-fourth wave length of the upper infinite attenuation frequency, f_4 , in length. The short-circuited ends of the folded sections are reflected at the open ends of these sections as high impedances. Hence the folded sections appear as parallel tuned circuits in series with each other.

The length L_3 of each of the shunt stub sections **20** and **21** from the shorted end thereof to the center conductor **11** is approximately one-fourth wave length long at the mid-frequency of the pass band. The short-circuited end of each of the shunt sections is reflected to the opposite end thereof as a high impedance, and hence these stubs appear as parallel tuned circuits shunted between the center conductor section and the outer conductor section of the coaxial filter.

The characteristic impedances of the shunt stub sections **20** and **21** and the folded line sections are determined by the cutoff frequency and the desired characteristic impedance of the filter as a whole. Let Z_1 be the characteristic impedance of the first folded section L_1 , let Z_2 be the characteristic impedance of the second folded section L_2 and Z_3 be the characteristic impedance of the coaxial shunt stub sections. Then the relation between the characteristic impedance of the folded sections and the cutoff frequencies will be given by the equation:

$$\frac{1}{\rho} = \frac{1 + \cos 2\theta}{\cos 2\theta + \cos 2\theta\alpha}$$

where:

$$Z_2 = Z_3 = \rho Z_1$$

$$\alpha = \frac{L_2 - L_3}{2L_1}$$

$$\theta = \frac{\omega_0 L_1}{V}$$

where:

ω_0 = cutoff frequency (upper or lower) and V = propagation velocity through the filter which is equal to approximately 3×10^{10} cm./sec.

The relation between the characteristic impedance of the shunt stub-section as **20** or **21**, the folded section as **12** or **14**, and the overall filter characteristic impedance, K_0 , is given approximately by the equation:

$$Z_1 Z_2 = K_0^2 (1 - \cos \pi\alpha)$$

It has been found that in order to avoid de-

tuning the series folded sections **12** and **14** due to the distributed capacitances of the shunt stub-sections **20** and **21**, the shunt stub sections should make contact with the cylindrical conductors at a point approximately one-eighth wave length from the center gap **15**.

A coaxial "m"-derived type band-pass filter of the type described above will provide satisfactory operation at relatively high radio frequencies. The attenuation in the suppression regions rises very rapidly on either side of the cutoff frequencies until it reaches an infinite value at the respective infinite attenuation frequencies.

While there has been described what is at present considered to be the preferred embodiment of this invention, it will be obvious to those skilled in the art that various changes and modifications may be made therein without departing from the scope of the invention.

The invention claimed is:

A coaxial transmission line band-pass filter comprising an outer coaxial conductor, an inner conductor comprising a first folded-section transmission line consisting of a center conductor surrounded by a cylindrical conductor a quarter wavelength long at a frequency just outside one end of said band pass which is short-circuited to said center conductor at one end thereof and open at the other end thereof, said inner conductor also comprising a second folded-section transmission line consisting of a continuation of said center conductor surrounded by a second cylindrical conductor a quarter wavelength long at a frequency just outside the other end of said band pass which is short-circuited to said center conductor at one end thereof and open at the opposite end thereof, the open ends of said coaxial conductors of said first and second folded sections being adjacent and spaced to form a gap, and first and second shunt coaxial line stub sections, a quarter wavelength long at the center frequency of said band pass, coupled between said outer conductor and said first and second folded sections, respectively, at points spaced substantially one-eighth wavelength at the center frequency of said band pass from said gap.
